UNITED STATES PATENT OFFICE.

JOHN E. WIENEKE, OF UNION, MISSOURI.

MEASURING GROCERY BIN.

1,419,338.

Specification of Letters Patent. Patented June 13, 1922.

Application filed August 18, 1921. Serial No. 493,297.

To all whom it may concern:

Be it known that I, JOHN E. WIENEKE, a citizen of the United States, residing at Union, in the county of Franklin and State 5 of Missouri, have invented certain new and useful Improvements in a Measuring Grocery Bin, of which the following is a specification.

My invention relates to grocery bins for 10 holding such articles as sugar, coffee, flour, etc., and its principal object is to provide such a bin wherein a predetermined quantity will be discharged therefrom into a drawer.

15 A further object of the invention is to provide a bin of this character which includes a hopper for retaining the material to be discharged and a sliding receptacle into which the material flows from the hopper, together with an automatic valve mechanism, which upon withdrawal of the drawer will close the outlet opening of the hopper and reversely upon returning the drawer to normal position opens the valve to permit 20 the drawer to become again filled with the material.

With the preceding and other objects which may become apparent from the following disclosure, the invention consists in 30 the novel construction and arrangement of parts and operation to be hereinafter specifically referred to, illustrated and defined in the subjoined claim.

In the drawings:

35 Fig. 1 is a front end elevation of the bin, parts being broken away;

Fig. 2 is a vertical sectional view of the same;

40 Fig. 3 is a similar fragmental view illustrating the drawer in its outward position and the valve in closed position.

Fig. 4 is a horizontal sectional view taken on line 4—4 of Fig. 2.

45 Fig. 5 is a perspective of the valve embodied in the invention.

Fig. 6 is a sectional view of the bin.

Fig. 7 is a similar view and taken at right angles to Figs. 6, and

50 Fig. 8 is a perspective of one of the elements embodied in the combination.

Referring in detail to the drawings where in like characters of reference denote corresponding parts throughout the several views, the numeral 5 designates a bin or casing provided with a hinged cover 6. Arranged in the bin or casing 5 is a hopper 7

having inclined walls 8 provided with a discharge opening 9 at their lower ends. Screwed to the lower ends of these walls 8 and surrounding the opening 9 is a wear 60 plate 10.

Arranged in the casing 5 below the hopper 7 is a rectangular drawer receiving compartment 11, in which a sliding drawer or scoop 12 is mounted. The inner face of the 65 side walls of the drawer receiving compartment 11 is provided with longitudinal grooves or guideways 13 at their upper edges, and slidably mounted in these grooves or guideways 13 is a gate valve 14. Depending from the valve 14 is an abutment member 15 adapted to be engaged by the rear end of the drawer or scoop 12 to shift the valve to open position, as illustrated in Fig. 2. In order to move the valve to closed position 70 upon withdrawal of the drawer or scoop 12, an angularly disposed resilient catch 16 is mounted upon the under face of the gate valve 14, at the forward end thereof adapted to engage in a recess 17 in the inner face 80 of the rear wall or scoop 12. A wear plate 18 embraces the upper edge of this wall and extends within the recess 17.

Assuming the hopper 7 to be filled with material the same will be discharged into 85 the drawer or scoop 12. As shown in Figs 2 and 6, the valve 14 is normally in open position with the resilient member 16 disposed in advance of the rear wall or scoop or drawer, upon withdrawal of the drawer or 90 scoop the resilient member will engage with the recess 17, and the valve will move forwardly to cover the opening 10 in the hopper, as shown in Fig. 3. After the contents of the drawer have been dumped therefrom, 95 the latter is slid rearwardly to its normal position and the rear wall thereof contacting with the member 15 moves the valve rearwardly to a position to one side of the opening 10, as shown in Figs. 2 and 6. 100

The embodiment of the invention herein illustrated and described is a practical example of the same, but it is to be understood that changes and modifications may be resorted to, and my limits of such modifications are only governed by what is claimed. 105

What I claim is:

The combination of a bin, of a hopper mounted therein having inclined walls which define a discharge opening at the 110 lower end thereof, a drawer compartment extending transversely of the hopper and

provided with opposed longitudinal grooves, a gate valve slidable in the grooves, a depending abutment carried by the plate valve to be engaged by the rear end of the drawer upon inward movement of the same to move the valve to open position, a resilient angularly disposed plate carried by the forward

end of the valve to be engaged by the rear face of the wall of the drawer, whereby to move the valve to closed position upon withdrawal of the drawer. 10

In testimony whereof, I affix my signature.

JOHN E. WIENEKE.
